THREADED FASTENER FOR PIPE SUPPORTING RINGS

Carl P. Rider, Columbia, and Samuel Y. Keller, Hellam,
Pa., assignors to Grinnell Corporation, Providence,
R.I., a corporation of Delaware

Filed Sept. 14, 1961, Ser. No. 66,719

Term of patent 14 years

(Cl. D54—9)

FIG. 1

FIG. 2

FIG. 3

FIG. 4

FIG. 5

FIGURE 1 is a front elevational view of a threaded fastener for pipe supporting rings embodying our new design with a broken line showing of a portion of a threaded shaft, and a pipe enclosed in the hanger strap, which are included only for purposes of illustration.

FIGURE 2 is a top plan view thereof with portions omitted for convenience of illustration.

FIGURE 3 is a bottom plan view thereof with portions omitted for convenience of illustration.

FIGURE 4 is a front elevational view thereof with portions omitted for convenience of illustration.

FIGURE 5 is a side elevational view thereof with portions omitted for convenience of illustration.

We claim:

The ornamental design for a threaded fastener for pipe supporting rings, substantially as shown and described.
